United States Patent Office.

ANNA NIFFELEER, OF CHICAGO, ILLINOIS.

Design No. 3,005, dated April 21, 1868.

DESIGN FOR A SAD-IRON.

The Schedule referred to in these Letters Patent and making part of the same.

TO ALL WHOM IT MAY CONCERN:

Be it known that I, ANNA NIFFELEER, of Chicago, county of Cook, State of Illinois, have invented a new Design for a Sad-Iron; and I do hereby declare that the following is a full and exact description thereof, reference being had to the accompanying drawings, making part of this specification.

My invention consists in a novel design for a sad-iron, of that class which is to be heated by the use of charcoal placed within the body of the instrument and burned therein.

The body is made with the handle attached to the lid, as shown in the drawing. Around the sides, near the lower edge, is a projecting base, at the upper edge of which are holes, as shown. There is also a damper at the rear end, and in each side of the body there are two circular recesses, in which is a series of small holes or perforations, as represented in the drawing; the whole thus forming a neat and ornamental design for a sad-iron.

Having thus described my invention, what I claim is—

The design for a sad-iron, as herein described and shown.

ANNA NIFFELEER.
